UNITED STATES PATENT OFFICE.

BENJAMIN DAVIES, OF HOBOKEN, NEW JERSEY, ASSIGNOR TO L. STRAUS & SONS, OF NEW YORK.

DESIGN FOR A GLASS VESSEL.

SPECIFICATION forming part of Design No. 26,190, dated October 13, 1896.

Application filed September 5, 1896. Serial No. 605,032. Term of patent 7 years.

To all whom it may concern:

Be it known that I, BENJAMIN DAVIES, a subject of the Queen of Great Britain, and a resident of Hoboken, in the county of Hudson and State of New Jersey, have invented and produced a new and original Design for Glass Vessels; and I do hereby declare the following to be a full, clear, and exact description of said invention, reference being had to the accompanying drawings, and to the letters of reference marked thereon, which form a part of this specification.

In the drawings, Figure 1 is a plan view of a dish ornamented with my design, and Fig. 2 represents a cross-sectional view of the same.

The leading feature of my design consists of six pairs of substantially parallel deep grooves extending from edge to edge, the outer groove of each pair being shorter than the inner groove, the said outer grooves collectively forming two crossed triangles and the inner grooves forming a six-pointed star, the points of which are between the apexes of the triangles, and the fields or spaces between the different deep grooves being occupied by rosettes of finer grooves.

The outer deep grooves are represented in the drawings at *a*, and the inner deep grooves are represented at *b*, the ends of the former

converging at *a'* and the ends of the latter converging at *b'* and forming points which terminate at the centers of corrugated flutes, forming the outline or margin of the dish.

In the center field of the design is a star *c* 35 of straight crossing grooves and in the six next smaller and surrounding fields are smaller star-patterns *d*, the small triangular spaces between the stars *c* and *d* being occupied by fan-figures *e*.

Near the margin of the dish the converging ends of the deep grooves *a* and *b* are connected by short deep grooves *f*, forming six-sided fields near the apexes of the triangles, which are occupied by star-patterns *g*, alternating with smaller five-sided fields, which are occupied by rosettes *h* of radiating grooves.

Having thus described my invention, what I claim is—

The design for the ornamentation of glass vessels substantially as herein described and shown.

In testimony whereof I affix my signature in presence of two subscribing witnesses.

BENJAMIN DAVIES.
